UNITED STATES PATENT OFFICE

2,155,787

CENTRIFUGE FOR CONTINUOUSLY SEPARATING SEMISOLID CONSTITUENTS

Erik August Forsberg, Stockholm, Sweden, assignor, by mesne assignments, to The De Laval Separator Company, New York, N. Y., a corporation of New Jersey

Application August 27, 1934, Serial No. 741,653
In Sweden September 2, 1933

7 Claims. (Cl. 233—22)

In centrifugal separators in which two liquids are separated the one from the other (e. g., common milk separators) it is generally not difficult continuously to discharge the separated products, as the nature of liquids makes them easily movable within and out of the heavy and light liquid zones formed in the separating chamber. The conditions, however, are different if one of the separated products, and particularly the heavier one, consists of or largely comprises solids. These cannot leave the bowl automatically, but special arrangements are required for expelling them. A number of constructions, so-called sludge separators, have been devised for this kind of work.

There is, however, also, a third condition to which neither the common separators nor the sludge separators are adaptable and that is when one separated product is of a semi-solid doughy nature. In case it is heavier than the liquid it has been possible in some instances, as for example in the so-called yeast separators, to secure acceptable results by providing the bowl with narrow outlets at or in the neighborhood of the periphery and by giving the bowl wall such a shape that the separated matters slide toward such outlets. However, bowls of this type work in a satisfactory manner with only certain materials and do not allow the discharge of the heavier separated product in a more or less highly concentrated form, which is often desirable. And they are of course quite useless if the semi-solid product is lighter than the liquid.

The last named condition sometimes exists. As a typical example may be mentioned the separation of paraffin from mineral oil (crude oil, distillate or distillation residues) after it has been diluted with a heavy liquid (trichlorethylene or the like) and chilled to a low temperature. The paraffin is removed as the lighter constituent and accumulates in the central part of the bowl, whence it outflows to and through the outlet for the lighter constituent. Such a process is described in the Backlund Patent No. 1,676,069. In carrying out this process it has been customary to supply the mixture in the usual manner through a central feed tube to the separating chamber and distribute the mixture therein through vertically aligning holes in a pile of conical discs. The separated heavy solution of oil and solvent flows from the peripheral portion of the bowl upwardly into a chamber in the bowl neck and thence out over a weir plate which is exchangeable or adjustable for regulation of the level. The separated lighter doughy

or viscous paraffin fills a chamber between the control feed tube and the inner edges of the discs and thence flows upwardly over a collar projecting inward from the bowl top and through holes in the bowl top or neck above the collar.

A bowl of this type works in a satisfactory manner as long as the paraffin is of not too high a viscosity and the quantity is not too large. Under these conditions the radial differences of level which are necessary for forcing the paraffin axially to the edge of the collar are not greater than is permissible from the point of view of practical and convenient dimensions of the bowl. However, if the paraffin has great inner friction (that is, if it be coarse crystalline and especially needle crystalline), large radial differences of level are of course required in order to produce the axial flow which is necessary for the discharge of the paraffin. The condition will of course be similar if the quantity of paraffin be large and therefore necessitate a great axial rate of flow. In these circumstances it is necessary either to facilitate the axial movement of the mass by special mechanical scraper devices, or to shorten the axial path through which the mass must move in order to leave the bowl. Constructions designed to accomplish the first of these results are known (see Forsberg Patent No. 1,699,286) and sometimes operate efficiently, although they introduce an undesirable complication. In order to shorten the axial path of flow the bowl has been provided with paraffin outlets in both ends, but with this expedient also the capacity of the bowl is limited, not by its separating ability, but by its ability to discharge the paraffin, unless the bowl is made impractically low in relation to its diameter. With present arrangements it is thus not possible fully to utilize the real separating capacity of the bowl when the quantity of paraffin is large or when the paraffin is heavy, without using expensive and complicated mechanical constructions.

The present invention comprises an arrangement that makes it possible to take out the separated lighter constituent in other places than at the ends of the chamber in which the said constituent accumulates in the bowl. The invention thus makes it possible to take out the separated mass in several different places at a small axial distance one from the other. The separated product therefore has to move only a desired short distance in axial direction, and at each place of discharge only a desired small portion of the whole quantity need be taken out. Thereby, even with an especially heavy sepa-

rated product, or in case the relative quantity of such product should be considerable, the radial differences of level which are possible in practice become sufficient for producing the axial movements that are necessary in order to remove such product.

In the drawing:

Fig. 1 is a vertical sectional view of a centrifugal separator embodying the invention.

Fig. 2 is a partial vertical section of a modification.

Fig. 3 is a detail perspective view of one of the scrapers, shown in Fig. 1, for deflecting the lighter separated material in such manner as to facilitate its discharge from the separator bowl.

The mixture to be separated is supplied through the central tube 1 and passes through the channels 2 and the holes 3 to the discs 4, between which the separation takes place. The heavy liquid discharges through channels 5, which may be provided with devices 7 for regulating the discharge level, which devices are shown in Fig. 1 as regulating screws but may be of other constructions, as, for example, exchangeable rings, as shown at 1a in Fig. 2. The lighter constituent collects in the chamber 8, whence it is to be removed from the bowl. If this latter constituent were free flowing, as, for instance, the cream in a common milk separator, it could directly discharge through the outlet 10. A certain difference of pressure is of course necessary in order that a discharge shall take place, but if the material has a low viscosity, a very small radial difference of level is sufficient for the discharge of even comparatively large quantities. If, on the other hand, the material has a high viscosity, its inner surface must assume a slanting position, so that almost the whole chamber to the central tube 1 becomes filled and the bowl becomes clogged.

In order to facilitate the discharge from the bowl of the separated product in question and thus avoid the inconveniences referred to above, one or, preferably, several scrapers 11, 12 are provided in the chamber between the inner rims of the discs 4 and the central tube 1, the said scrapers working into the rapidly rotating surface of the lighter separated product and throwing it in axial or nearly axial direction towards the open end of the bowl, which, in the type of machine shown, is its upper end. The shape of the scrapers may be varied. A suitable arrangement is to construct the scrapers as spiral-formed chutes, as indicated at 11. Another shape is shown in Fig. 2, where the scraper simply consists of a bent wing 12. The scrapers are suitably fixed to a stationary holder, which may be in the form of a tube 13. The scrapers are placed at different heights and on different radii, so that a higher scraper does not hinder the material from being thrown out from a lower one. It is of course also possible to arrange two or more scrapers at the same height in order to obtain a more symmetric load. The inner surface of the separated mass assumes a wave-like aspect, as indicated at 6 in the figures. The axial distance between the scrapers proper and between the outermost scraper and the outlet 10 is selected with regard to the amount and nature of the material which is to be brought away. The greater the number of scrapers in axial direction, the smaller the amount of the mass which will be removed in each place and the greater the sloping which can be permitted for each wave of the inner surface; both of which condi-

tions contribute to increasing the possibilities of the mass to discharge.

The mass being thrown out axially hits a deflector 14, which causes its movement to deviate to the side. The deflector may be in fixed relation to the holder 13 or to the collecting vessel 9, as shown in Fig. 2, or it may be fixed to the bowl, as in Fig. 1. The former construction is the simpler, but the latter has the advantage that the deflector is kept free from the mass by the centrifugal force.

The holder 13 may be a fixed one or it may to a certain degree participate in the rotation of the bowl. The latter arrangement is better adapted to keeping the deflector 14 clean and (principally) to reducing the wear of the scrapers 11 or 12 and the stresses on the parts. If the mass is of a coarse grinding nature, the wear and the stresses on the scrapers would become too great if their relative speed were kept at a value which corresponds to the usual speed of separator bowls. The holder and the scrapers fixed thereto should therefore be caused to rotate in the same direction as the bowl, but at a reduced speed. The desired movement is suitably generated by allowing the holder to be rotated by contact with the separated mass but braking it with a certain force; the speed of course being regulated by the force of braking applied. Any type of braking may be used: mechanic, hydraulic, electric or magnetic. In Fig. 2, 15 represents a mechanical braking member consisting of a brake-band carried by an arm 16 secured to the machine frame. The tubular holder 13, to which the scrapers 12 of Fig. 2 are secured, is carried by the upper collecting vessel 9. If this vessel were laid loosely upon the lower collecting vessel (which is secured to the main frame), it would, unless restrained, freely rotate, due to the rotary action of the separated paraffin upon the scrapers 12. However, the brake-band 15 restrains vessel 9, holder 13 and scrapers 12 from free rotation. The tension of the brake-band is adjusted to allow the members 9, 13 and 12 to rotate, but at a reduced speed, so as to allow the scrapers to function as described and at the same time avoid imposing upon them any dangerous stress or strain.

The machine works in the following manner.

After the bowl has been started and the liquid has been admitted, separated lighter product begins to collect in the chamber 8 which by and by becomes filled towards the center. After some time the mass reaches the scrapers and begins to be thrown out in axial direction. Between the scrapers, however, the mass continues moving inwards to the center, ridges or swells as those shown at 6 in Fig. 1 thereby being formed. Under the influence of the centrifugal force the mass begins to float axially from the ridges towards the valleys, which are kept free from the mass by the scrapers. An equilibrium is reached when the movement of the mass towards the valleys takes place at the same rate as the separating procedure. By suitably choosing the form, size and number of the scrapers, and if necessary also their rotation speed, the scraper device can be regulated to cope with separated material of different amounts and nature.

What I claim and desire to protect by Letters 70 Patent is:

1. A centrifugal separator adapted for the separation of constituents of which the lighter is comparatively not free-flowing, comprising a rotatable bowl provided with an outlet for the 75

lighter separated constituent, one or more scrapers positioned in that region of the bowl nearest its center and adapted, as the separated lighter mass penetrates into said region, to work into said mass and displace it in a substantially axial direction toward said outlet, a freely rotatable holder to which said scraper or scrapers are secured whereby the separated constituent tends to rotate the scraper or scrapers, and means to

5 said mass and displace it in a substantially axial direction toward said outlet, a freely rotatable holder to which said scraper or scrapers are secured whereby the separated constituent tends to rotate the scraper or scrapers, and means to
10 brake the holder so as to compel the scraper or scrapers to rotate at a speed below the rotation speed of the separated mass.

5. In a centrifugal separator adapted for the separation of constituent materials of which the lighter is comparatively viscous and provided with an outlet for such lighter viscous material, means for facilitating the removal of said lighter viscous material from an annulus thereof surrounding the center of the bowl comprising a relatively stationary open trough scraper located at the central part of the bowl and of short length relative to the radius of the bowl and whose outer end is distant from the periphery of the bowl, said scraper having a warped surface starting from its outer end at approximately the inner surface of the annulus as a spiral of decreasing radius and gradually changing in an upward direction to approximately a radial plane with its discharge end substantially

25 inside the exit from the bowl.

6. In a centrifugal separator adapted for the separation of constituent materials of which the lighter is comparatively viscous and provided with an outlet for such lighter viscous material, means for facilitating the removal of said lighter viscous material from an annulus thereof surrounding the center of the bowl comprising a relatively stationary open trough scraper located

30 wholly in the central part of the bowl and extending inward and upward from said annulus and having a center line starting as a spiral of decreasing radius approximately in a plane at right angles to the axis of the bowl and gradually changing in a smooth curve to a plane approximately parallel with the center line of the bowl, different scrapers being positioned on different radii of the bowl and at different distances from said outlet so as to form substantially non-interfering columns of the lighter viscous outflowing material.

7. In a centrifugal separator adapted for the separation of constituent materials of which the lighter is comparatively viscous and provided with an outlet for such lighter viscous material, means for facilitating the removal of said lighter viscous material from an annulus thereof surrounding the center of the bowl comprising a relatively stationary open trough scraper located

35 wholly in the central part of the bowl and extending inward and upward from said annulus and having a center line starting as a spiral of decreasing radius approximately in a plane at right angles to the axis of the bowl and gradually changing in a smooth curve to a plane approximately parallel with the center line of the bowl and adapted to pare off a thin strip from the interior of the rapidly moving annulus and, while the material is still moving due to its

40 inertia, guide it in an axial direction first toward the center of the bowl and then in an axial

45 direction toward the exit of the bowl.

8. In a centrifugal separator adapted for the separation of constituent materials of which the lighter is comparatively viscous and provided with an outlet for such lighter viscous material, means for facilitating the removal of said lighter viscous material from an annulus thereof surrounding the center of the bowl comprising a relatively stationary open trough scraper located

50 wholly in the central part of the bowl and having a warped surface starting at the inner surface of the annulus as a spiral of decreasing radius and gradually changing in an upward direction to approximately a radial plane and adapted to pare off a thin strip from the interior of the rapidly moving annulus and, while the material is still moving due to its

55 inertia, guide it in an axial direction first toward the center of the bowl and then in an axial direction toward the exit of the bowl.

9. In a centrifugal separator adapted for the separation of constituent materials of which the lighter is comparatively viscous and provided with an outlet for such lighter viscous material, means for facilitating the removal of said lighter viscous material from an annulus thereof surrounding the center of the bowl comprising a relatively stationary open trough scraper located

60 wholly in the central part of the bowl and from their outer ends extending inward and upward from said annulus, each of which has a center line starting from its outer end as a spiral of decreasing radius approximately in a plane at right angles to the axis
